Benj^{tt} Wardwell of Fall River, Mass & Ephraim R. Barstow of Providence, R. I.

Letters Patent No. 819, dated July 29, 1856.

The schedule referred to in these Letters Patent and making part of the same.

To all whom it may concern:

Be it known that we, Benjamin Wardwell, of Fall River, in the County of Bristol, and State of Massachusetts, and Ephraim R. Barstow, of Providence, in the County of Providence and State of Rhode Island, have invented or produced a new and original design for a book stove, and we do hereby declare that the following is a full, clear, and exact description of the same, reference being had to the annexed drawings making a part of this specification, in which,

Fig: 2, is a back view of do,

Fig: 3, is a plan or top view of do.

Similar letters of reference indicate corresponding parts in the several figures.-

The bottom of the side plates A, of the stove, has a border (a) upon it, said border being also at the bottom of the back plate B, of the stove, see figs. 1 and 2; At the top of the side plates A, there is a border (b), said border being also at the top of the back plate B.-

On the back plate B, there are three panels (c), (c), (c), the centre panel being much wider than the other two. These panels have borders (d) around them, said borders being formed of scolloped projections (a') and small trefoils (b'), as shown in fig. 2. The border (a) at the bottom of the side and back plate, is formed of shell like projections (c), connected by trefoils (d), the upper border (b) is formed of scolloped and shell like projections (e) connected by trefoils (f). -

C, represents the door of the oven. The door has a border (c) around it, precisely similar to the borders (d), around the panels (c). This door has a shield (f) at its centre, the shield having a foul anchor (g) upon it. The shield is encompassed by an oval wreath of leaves (h). set scrolls (i) are formed at each corner of the door C. -

D, represents the door of the fire chamber. This door has a border (k) around it, precisely similar to the borders (d), (e), and an ornament (l), at its centre enclosed by a rectangular bead or projections (m). -

E, is the door of the ash pit, having a border (n) around it, precisely similar to the borders (d), (e), (k), and an oval or elliptical ornament (o) at its centre. -

F, represents the hearth plate having a border (p) around its edge, said border being precisely similar to the borders (d), (e), (k), (n). -

G, represent the legs of the stove, which legs have scrolls (q) upon them and scolloped projections (r) at their upper parts. -

We claim the form or configuration of the parts or ornaments herein described; the whole forming a new and original design for a book stove.
